Lacy & Lacy, Attorneys

UNITED STATES PATENT OFFICE.

JOHN LUNDE, OF CROOKSTON, MINNESOTA.

SIGNAL BOND.

Application filed September 25, 1922. Serial No. 590,532.

To all whom it may concern:

Be it known that I, JOHN LUNDE, a citizen of the United States, residing at Crookston, in the county of Polk and State of Minnesota, have invented certain new and useful Improvements in Signal Bonds, of which the following is a specification.

This invention relates to means for bonding track rails and fish plates whereby upon 10 breakage in either the rail or the fish plate a signal will be operated to notify a central station of the location of the break and also halt an approaching car or train. The invention is illustrated in the accompanying 15 drawing and will be hereinafter fully set forth.

In the drawing:

Figure 1 is a side elevation of a portion of a railroad track having my improved 20 bonding means applied thereto;

Fig. 2 is a transverse section on the line 2—2 of Fig. 1, and

Figs. 3 and 4 are detail views of a bonding terminal.

In the drawing, the reference numeral 1 indicates the meeting ends of alined track rails and 2 indicates fish plates of the usual form secured to said track ends by bolts 3 and bridging the joint. The bonding members 30 consist of sections of cables 4 consisting of strands of copper wire twisted together to attain strength as well as flexibility, and terminals 5, each having a tubular body or thimble 6 at one end in which the ends of the cables are received and secured by welding, pinching or other convenient means. The said tubular members 6 are of metal so as to constitute conductors and one end thereof is open to receive the

cables, as will be readily understood, while the other end is closed by a head 7 from which a flat tapered tongue or attaching member 8 projects, it being noted particularly upon reference to Fig. 4 that the attaching tongue 8 is in the same plane with one side portion of the head 7 and the tubular terminal 6 so that an extended flat contact between the terminal and the side of a rail or a fish plate may be obtained.

In applying the bonding members in accordance with my invention, one terminal 5 of each bond is applied against the head of a rail 1 as close to the end thereof as is feasible and is secured thereto by welding,

brazing or some other equivalent method 55 whereby a mechanically strong union having low electrical resistance between the terminal and the rail will be effected. The cable 4 is carried along the side of the rail head and is then turned downwardly at the 60 end of the fish plate and the remaining terminal 5 is secured against the outer face of the fish plate in the same manner that the first described terminal was secured to the track rail. The bonding members provide 65 conductors of low resistance whereby the currents flowing through the track rails will be carried from points at the ends of the rails to the fish plates so that, if a break occurs in the rails or in the fish plates, the 70 current will be interrupted and the circuit broken, whereupon the signal at the central station will be operated and the attendants at once notified of the location of the break, the track signal being simultaneously set to 75 close the block in which the break occurs. My device is exceedingly simple, may be 80 readily applied to any rail, and will not be disturbed by the passage of cars or trains over the track, the bonds being located on the outside of the track where they will not be subject to breakage or disturbance by the car wheel flanges. My invention provides 85 a path of very low resistance to the flow of the electric current which, otherwise, has a metal path of very high resistance. Owing to rust upon the rails and fish plates, the 90 resistance at various times is sufficient to break the circuit in an unbonded joint, and set the signal at danger when the track is really clear.

Having thus described the invention, what is claimed as new is:

The combination with alined rails, and 95 fish plates secured to and bridging the joint between the rails, of bonding members each consisting of a plurality of strands of copper wire twisted together and terminals mechanically and electrically united with the 100 ends of said wire, one terminal of each bonding member being electrically and mechanically united with a rail at the end of the same and the other terminal of the same member being electrically and mechanically 105 united with the adjacent fish plate at the end of the same.

In testimony whereof I affix my signature.
JOHN LUNDE. [L.S.]
